HOISTING MACHINE

Robert C. Post, Englewood, N. J., assignor to
Post & McCord, a Corporation of New York

Application June 20, 1929. Serial No. 372,290

11 Claims. (Cl. 188—82)

My invention relates to improvements in hoisting machines of the type in which loads may be raised and lowered by winding and unwinding a cable on a hoisting drum.

Usually such machines are operated by an electric motor or other prime mover which drives the drum in hoisting direction through the medium of a clutch. When lowering a load the clutch is thrown out and rotation of the drum is controlled by means of a service brake acting thereon. Usually the service brake is operated by a foot pedal under control of the operator. The clutch is normally disconnected and must be held manually in operating or engaging position, the purpose of this being to permit of more accurate control of the load. Thus the operator may let the clutch slip slightly so as to ease up the load to a desired point. To hold the load at any fixed point, the winding drum is usually provided with ratchet teeth adapted to be engaged by a pawl which can readily be thrown into engaging position by the operator. To prevent the motor from running in reverse direction an automatic brake is provided on the rotor shaft which is effective only against reverse rotation of the motor. Thus if for any reason power should fail while raising a load, the automatic brake will prevent the load from falling so long as the operator holds the clutch lever in engagement. This gives the operator time to throw the pawl into engagement with the ratchet. Furthermore, the operator could stop the rotation of the drum by depressing the pedal and thus applying the service brake.

However, the hoisting drum is normally free and neither the motor brake nor the service brake will come into play automatically to stop the drum; for the motor brake although automatically stopping the motor will not stop the drum unless the clutch is held in engaging position and the service brake is inactive unless the pedal is depressed. An operator might be suddenly stricken, releasing the clutch lever and the pedal, and then there would be nothing to prevent the load from falling. There is also a possibility that an operator might become excited or confused, releasing the clutch and delaying depression of the pedal until the load had gathered sufficient momentum to break the hoisting cable or wreck the machine.

It is an object of my invention to overcome such dangers by providing an automatic safety brake which will automatically come into play to prevent uncontrolled dropping or lowering of the load.

Another object of my invention is to provide a safety brake which is normally held in operative position but is thrown out of engagement with the drum only when the service brake is in controlling position.

Another object is to provide a safety brake of a type which when in operative position will permit rotation of the drum in hoisting direction but will permit rotation of the drum in reverse or lowering direction.

Another object of the invention is to provide a safety brake which is maintained in inoperative position by power means, so that in case of failure of the power, the safety brake will automatically be thrown into engagement to stop the drum against reverse or unwinding rotation.

Another object of the invention is to provide a safety brake of the character described above, with an auxiliary manual control, whereby the brake may be disconnected from power so that it will move automatically into operative engagement with the winding drum.

Other objects and advantages of my invention will appear in the following description of a preferred embodiment and thereafter the novelty and scope of the invention will be pointed out in the claims.

In the accompanying drawing;

Figure 1 is a view in side elevation of a single drum hoisting machine provided with my improved safety brake, certain portions of the machine being removed to reveal features of the invention;

Fig. 2 is a plan view of the hoisting machine, and

Figs. 3 to 5 are detail views of parts of the safety brake mechanism, showing one of the safety brake shoes in three different positions.

As shown in the accompanying drawing, the hoisting machine is provided with a base 10 on which are mounted two brackets 11. These brackets provide bearings for the rotor shaft 12 of a motor 13. The shaft 12 is provided with a servo-brake consisting of a brake wheel 14 which is adapted to be engaged by brake shoes 15 and 16 supported on a yoke 17. The latter is mounted to oscillate on a stud supported in a bracket 18 secured to the base 10. The shoe 16 is directly connected to one arm of the yoke, while the shoe 15 is connected to the other arm of the yoke by means of a link 19. When the motor shaft turns in normal direction, as shown by the arrow in Fig. 1, the brake is ineffective and the shoe 15 merely trails along the brake-

105

110

wheel 14, because the point of attachment of the shoe 15 to the link 19 is above a line passing through the shaft 12 and the point of attachment of link 19 to the yoke. However, should the rotor be turned in the opposite direction, 5 the shoe 15 would be dragged downward by the brake wheel 14, causing the yoke 17 to oscillate and force the opposite shoe 16 also into operative engagement with the brake wheel.

The brackets 11 also provide bearings for a 10 shaft 20 on which is mounted a cable drum 21. The shaft 20 is driven by the motor 13 through a train of gears 22 so as to turn in the direction of the arrow in Fig. 1. The cable drum 21 is connected to the shaft through a friction 15 clutch 23 and this clutch is operated by means of a lever 24. The construction of the friction clutch may be of standard type and is not shown in detail in the drawing. The clutch is normally spring-pressed in disengaged position but 20 may be moved into and held in engaging position by operating a clutch lever 24.

The hoisting drum 21 is controlled by a service 25 brake when lowering a load and to this end the drum is formed at one end with a brake surface 25 adapted to be engaged by a brake band 26. This band is anchored at one end to a bracket 27, while the free end of the band is secured to an arm 28 fixed upon a shaft 29. The shaft 29 is journaled in the bed 10 and projects from the forward side of the machine. Secured to the projecting end of the shaft is a 30 pedal lever 30. A spring 30a holds the pedal lever normally in the position indicated by broken lines at A in Fig. 1.

The hoisting drum is also provided at one 35 end with ratchet teeth 31 adapted to be engaged by a pawl 32. The pawl may be thrown by hand into or out of engagement with the ratchet teeth. The ratchet teeth are so formed as to prevent 40 reverse rotation of the drum when engaged by the pawl, but will throw the pawl out of engagement when the drum is driven by the motor to raise the load.

Secured to the drum near the forward side of 45 the machine is a safety brake-wheel 33. This is adapted to be engaged by a pair of brake shoes 34 and 35 carried by a yoke 36 pivotally mounted on the adjacent bracket 11. The brake shoe 34 is directly connected to one arm of 50 the yoke 36 while the other brake shoe 35 is connected to the other arm of the yoke by means of an arm 37. This construction, it will be observed, is similar to that of the brake on the motor shaft with this difference, however, that 55 means are provided for raising the arm 37 sufficiently to prevent engagement of the brake shoe 35 with the brake wheel 33. This means consists of a rod 38 connected to the core 39 of a solenoid 40. The arrangement is such that 60 when the solenoid is energized it will lift the core and with it the arm 37 to the position shown in Fig. 5. However, when the solenoid is deenergized the arm will drop by gravity to the 65 position shown in Fig. 3. The brake shoe 35 is formed with a rearward projection 35a which is urged by a spring 41 against a stop 37a formed on the arm 37. When the drum is driven in 70 hoisting direction the parts will assume the position shown in Fig. 3 with the upper edge of the shoe 35 engaging and trailing on the brake wheel 33. When the direction of rotation of the drum is reversed the shoe 35 will be dragged down to the position shown in Fig. 4, thereby 75 rocking the yoke 36 on its pivot and forcing the

shoe 34 also into engagement with the wheel 33. The latter is thus arrested. When the solenoid is energized the arm 37 is lifted, raising the shoe 35 clear of the wheel 33 and a compression spring 36a acting on one arm of the yoke 36 restores the latter to the position shown in Fig. 1, with the other arm of the yoke bearing against a stop 36b. In this position the shoe 34 is withdrawn from engagement with the wheel 33.

On one side of the bed of the machine, I have provided a control box 42 with a controller handle 43 by which current to the motor may be controlled. Current is fed into the control box through a pair of mains 44 and 44a, respectively. Tapped across these mains are a pair of leads 45 and 46, respectively, of which the lead 45 runs directly to one terminus of the solenoid, while the lead 46 runs to a contact brush 47 carried by the pedal 30. This contact brush is adapted to engage a contact plate 48 which is connected by a line 49 to the other terminus of the solenoid 40. When the pedal is in its normal raised position A, the brush will be disconnected from the contact plate 48 and the solenoid will be deenergized and the safety brake will drop by gravity into a position to operate. When the pedal 30 is lowered to the operating position shown by full lines in Fig. 1, the circuit will be closed through the brush 47 and plate 48 to the solenoid 40, and the brake shoe 35 will be raised out of operative engagement with the brake wheel 33, as in Fig. 5. Thereafter further depression of the pedal 30 down to the limit of its braking stroke (indicated by broken lines B, in Fig. 1) will maintain the 100 electrical connection to the solenoid, so that the safety brake will continue to be held inoperative as long as the pedal is in operative position. To permit throwing out the safety brake by hand, even should pedal 30 be depressed, a hand switch 105 5 is provided in the lead 46.

An electric lamp 51 is bridged across the mains 44, 44a, so that the operator will know at any time whether current is available to operate the motor or safety brake; for in case of any failure in current, due to the blowing of the fuse or for any other reason, the lamp 51 will be extinguished.

The operation of the machine is as follows: To 110 raise a load, the operator throws in the clutch lever 24 and operates the controller handle 43 to energize the motor 13. This turns the drum in the direction of the arrow in Fig. 1 and although gravity is drawing the arm 37 downward there 115 will be no braking action of the safety brake because of the direction in which the drum and brake wheel are rotating. When lowering a load, the operator, having thrown the control handle 43 to cut off current from the motor, depresses the pedal 30 to apply the service brake. Then 120 the pawl 32 is thrown out of engagement with ratchet wheel 31, the clutch lever 24 is released and the load is lowered in the usual manner, under control of the service brake. The instant 125 the pedal is depressed to the position shown by full lines in Fig. 1 the brush 47 engages contact plate 48 energizing solenoid 40, which raises the arm 37 and holds the safety brake in inoperative position. If, for any reason, the operator 130 should remove his foot from the pedal 30, releasing the service brake, the pedal would spring up to the position A, under action of spring 30a, deenergizing the solenoid and permitting the 135 brake shoe 35 to drop to operative engagement with the safety brake wheel 33. Thereupon the 140

safety brake would act to arrest the hoisting drum and prevent the load from dropping. The same thing would occur even if the operator were lowering the load under control of the service 5 brake 26, should the current fail, because as soon as the solenoid is deenergized the safety brake will drop into operative position. The hand switch 50 could also be operated to deenergize the solenoid and throw in the safety brake. Thus, my 10 invention provides against any emergency which might arise and renders the operation of the cable hoist safe at all times and under all conditions.

I have shown my invention as applied to a single-drum hoisting machine, but it will be obvious that the same mechanism can be applied to a multiple-drum hoisting machine; in other words, a safety brake would be used with 15 each drum and would cooperate with the pedal 20 of the normal service brake of said drum in the manner described above.

While I have shown a specific embodiment of my invention, I wish it to be clearly understood that I do not limit myself to the particular type 25 of brake or other mechanism illustrated, but reserve the right to make such changes in details of construction and in form and arrangement of parts as fall within the spirit and scope of the following claims.

30 I claim:

1. In a hoisting machine, the combination with a hoisting drum, of a service brake, means for operating the service brake to control and arrest rotation of the drum, a safety friction brake normally operating to arrest rotation of the drum, and means for rendering the safety brake inoperative when the service brake is operated.

2. In a hoisting machine, the combination with a hoisting drum, of a service brake, means for 40 operating the service brake to control and arrest rotation of the drum in one direction, a safety friction brake normally acting to arrest rotation of the drum in said direction, and means controlled by the first-named means for rendering the safety brake inoperative when the service 45 brake is operated.

3. In a hoisting machine, the combination with a hoisting drum, of a service brake, a lever for 50 operating the brake to control rotation of the drum, a safety friction brake normally in position to arrest rotation of the drum, and means controlled by said lever for withdrawing the safety brake from operative position while the service 55 brake is in controlling position.

4. In a hoisting machine, the combination with a hoisting drum, of a service brake, a pedal for 60 operating the brake to control rotation of the drum, a safety friction brake normally in position to arrest rotation of the drum, and means controlled by said pedal for withdrawing the safety brake from operative position while the service 65 brake is in controlling position.

5. In a hoisting machine, the combination with a hoisting drum, of a service brake, a pedal for 70 operating the brake to control rotation of the drum, a safety friction brake normally in operative position to arrest rotation of the drum, power energized means for holding the safety brake in inoperative position, and a control device actuated by said pedal for energizing said means to

release the safety brake while the pedal is operated to control the service brake.

6. In a hoisting machine, the combination with a hoisting drum, of a service brake, a pedal for 80 operating the brake to control rotation of the drum, a safety brake normally in operative position to arrest rotation of the drum, electrically energized means for holding the safety brake in inoperative position, a switch in the circuit of said means and controlled by said pedal for energizing said means while the pedal is in position to control the service brake.

7. In a hoisting machine, the combination with a hoisting drum, of a service brake, a pedal for 90 operating the brake to control rotation of the drum, a safety brake normally in operative position to arrest rotation of the drum, electrically energized means for holding the safety brake in inoperative position, a switch in the circuit of said means and controlled by said pedal for energizing said means while the pedal is in position to control the service brake, and a hand switch 95 also in said circuit.

8. In a hoisting machine, the combination with a hoisting drum, of a service brake, a pedal for 100 operating the brake to control rotation of the drum, a safety brake normally in operative position to arrest rotation of the drum, electrically energized means for holding the safety brake in inoperative position, a switch in the circuit of said means and controlled by said pedal to close said circuit while the pedal is in position to control the service brake, a pair of power lines supplying current to said circuit and a lamp bridged 105 across said power lines.

9. In a hoisting machine, the combination with a hoisting drum, driving means for rotating the drum in hoisting direction, and means for disconnecting the drum, of a service brake, means for operating the same to control rotation of the drum in reverse direction, means normally holding the safety brake in operative position, said safety brake when in operative position permitting rotation of the drum in hoisting direction and arresting rotation of the drum in reverse direction, and power actuated means for withdrawing the safety brake from said operative position while the service brake is in controlling position.

10. In a hoisting machine the combination with a hoisting drum and a motor for driving the drum and a source of power for energizing said motor, of a safety brake for controlling rotation of the hoisting drum, restraining means energized from said source of power for holding the safety brake inactive, a service brake movable into position to control rotation of the drum, and means for disconnecting the restraining means from said power source when the service brake is in controlling position.

11. In a hoisting machine, the combination with a hoisting drum, of a service brake, means for operating the service brake to control and arrest rotation of the drum, a safety brake normally operating to arrest rotation of the drum, means interconnecting the brakes whereby when the service brake is operated the safety brake will be inoperative, and manually controlled means for restoring the safety brake to operative condition while the service brake is in operation.

ROBERT C. POST.
